UNITED STATES PATENT OFFICE.

MATTHEW C. YARWOOD, OF FALL RIVER, MASSACHUSETTS.

STOP MECHANISM FOR KNITTING-MACHINES.

SPECIFICATION forming part of Letters Patent No. 387,672, dated August 14, 1888.

Application filed December 22, 1887. Serial No. 258,666. (No model.)

To all whom it may concern:

Be it known that I, MATTHEW C. YARWOOD, of Fall River, in the county of Bristol, State of Massachusetts, have invented a certain new and 5 useful Improvement in Stop Mechanism for Knitting-Machines, of which the following is a description sufficiently full, clear, and exact to enable any person skilled in the art or science to which said invention appertains to 10 make and use the same, reference being had to the accompanying drawings, forming part of this specification, in which—

Figure 1 is a side elevation of a circular-knitting machine provided with my improvement, certain portions not deemed essential in illustrating the invention being omitted; Fig. 15 2, an enlarged side elevation of the shipping mechanism; Fig. 3, an enlarged side elevation of the presser mechanism, and Fig. 4 a view 20 showing certain details of construction.

Like letters and figures of reference indicate corresponding parts in the different figures of the drawings.

My invention relates more especially to 25 means for stopping the machine and removing the presser from the needles when a thread breaks; and it consists in certain novel features, as hereinafter fully set forth and claimed, the object being to produce a simpler, cheaper, 30 and more effective device for this purpose than is now in ordinary use.

The nature and operation of the improvement will be readily understood by all conversant with such matters from the following 35 explanation.

In the drawings, A represents the table, B the legs, and C the cylinder, of the machine, these parts being all of the ordinary form and construction, excepting as hereinafter specified.

A vertically-arranged standard, D, carrying a bracket, F, is mounted on the table A at one side of the cylinder C, and fitted to slide horizontally therein is a shaft, E, carrying a 45 presser-finger, f, of the ordinary construction at its inner end, which finger may be replaced by a wheel of the usual description, if preferred.

A coiled spring, b, is disposed on the shaft 50 E, one end of which abuts against the inner

face of the bracket F and the other against a fixed collet, d, on said shaft, said spring acting expansively to force the shaft outward and withdraw the presser f from the needles g in the cylinder C, thereby permitting the barbs 55 of said needles to open and prevent the loops of yarn from escaping from the shanks of the needles, as hereinafter described.

Pivoted to the horizontal portion of the bracket F there is a vertically-arranged bar, 60 G, which rests against a laterally-projecting stud, h, on the collet d, and pivoted to the vertical portion of said bracket there is a horizontally-arranged trencher-bar, H, provided with a stop, i, to prevent it from falling too 65 low when released.

Secured to the table A, below the bracket F, there is a platform, I, provided with a vertically-arranged standard, k, and fitted to work vertically on said standard there is a rod, v, 70 provided at its upper end with a horizontally-arranged arm, m, which overlaps the outer or free end of the trencher-bar H.

Disposed on the platform I there is a magnet, J, which is connected with the negative 75 pole of the ordinary galvanic battery N by the conducting-wire p, and secured to the bar v, above said magnet, there is an armature, L.

The bar H is provided with a shoulder or catch, q, adapted to engage and hold the bar 80 G, and the shaft E is screw-threaded at its outer end and provided with a nut, r, and check-nut r', which serve to regulate the extent of movement of the shaft and to adjust it into the proper position for contact with the 85 needles when thrown forward.

A vertically-arranged standard, K, is secured to the table A at one side of the cylinder C, and pivoted to the upper portion of said standard there is a trencher-bar, M, provided 90 with a notch or catch, z.

A vertically-arranged lever, O, is pivoted near its lower end to the standard K, the upper end of said bar being adapted to engage the catch z on the bar M, and its lower end 95 provided with a laterally-projecting pin, w.

A vertically-arranged lever, P, is also pivoted to the standard K, the upper end of said bar being provided with a notch, 24, in which the pin w rests.

A bracket, Q, is secured to the table A opposite and below the standard K, and fitted to work on said bracket there is a vertically-arranged rod, 25, carrying an arm, 26, at its 5 upper end, which is adapted to engage the outer or free end of the trencher-bar M, and at its lower end an armature, 27. Suspended from the bracket Q, over the armature 27, there is a magnet, Y, which is connected with the 10 magnet J by a conducting-wire, p.

Pivoted in a bracket, 28, to the frame-work of the machine there is an ordinary shipping-lever, 29, provided with a fork, 30, which stands astride a belt, 31, leading from the fast 15 driving-pulley 32 to the pulley 33 on the counter-shaft 34. This lever is provided with the usual fixed arm, 35, which swings with said lever and is adapted to engage the lower end of the bar P, as shown.

20 A coiled spring, 37, has one of its ends secured to the frame-work of the machine and the other to the fork 30 of the shipping-lever 29, said spring acting contractively to swing the shipping-lever inward and keep the arm 25 35 in forcible contact with the levers P, when said lever is set in a vertical position, as shown in Fig. 2.

A horizontally-arranged metallic bar, 40, is secured to the frame-work of the machine, said 30 bar being electrically insulated by rubber or glass bearings 41, and mounted on said bar there are a series of drop-boxes, R, corresponding in number with the number of threads or yarns 42 being used in the machine.

35 The drop-boxes consist, respectively, of a metallic case, 44, (see Fig. 4,) which is provided with an elongated slot, 45, in one of its sides, and is secured to the bar 40 by a clamp, 46.

40 A block of wood, 47, is secured within the case 44, and mounted on said block there is a metallic standard, 48, provided with a metallic arm, 49, which projects outwardly through the slot 45.

45 Pivoted horizontally in the upper end of the standard 48 there is a metallic lever, 50, which also passes through the slot 45 in the case 44, said lever being provided at its outer end with a crescent-shaped drop-weight, 51, 50 and on its inner arm with a counter-balance, 52.

The weight 51 is provided with a curved groove, 53, on its outer face, through which the thread 42 runs on its way from the bobbins S to the needles g in the cylinder C, said 55 thread passing through a guide hole or eye, 54, in the bar 40 at a point nearer the case 44 than the weight 51 is located, in order to enable said weight to bear constantly on said thread, the curved formation of the groove increasing the bearing-surface of the thread therein, and consequently the friction between the thread and weight, thereby keeping the lever 50 out of contact with the spring 65 when the thread is unbroken.

60 A metallic spring, 65, is secured to the inner side of the case 44, and so arranged that when the weight 51 is dropped by the breaking of

the thread 42 the inner end of the lever 50, on which said weight is mounted, will be brought into contact with said spring.

70

A conducting-wire, p, leading from the magnet Y, is connected with each of the drop-boxes R by branch conducting-wires p', attached to the arms 49, and there is a conducting-wire, 75 75 connecting the bar 40 with the positive pole of the battery N.

In the use of my improvement, the machine is threaded up by carrying the threads 42 through the eyes 54 in the bar 40, thence through the grooves 53 in the weights 51, and 80 thence through other suitable guides to the needles. The shaft E is then drawn forward until the presser f closes the barbs of the needles g, in which position it is secured by engaging the bar G with the catch q on the bar 85 H, the armature L being supported in a raised position by placing the arm m of the rod v on the outer end of the bar H, as shown in Fig. 3. The machine is now started up by shipping the belt 31 from the loose pulley 85 onto the 90 fast pulley 32, the arm 35 on the shipping-lever 29 being left pressing against the lower end of the lever P, and the levers O P secured in a vertical position by engaging the upper end of the lever O with the catch z on the lever M, 95 as best seen in Fig. 2. The machine having been started, as described, the tension on the threads will raise the weights 51 and the outer ends of the levers 50, thereby removing their inner ends from the springs 65 and keeping 100 the electrical circuit open; but if now one of the threads 42 breaks, its weight 51 will drop, causing the inner end of the lever 50 to be brought into contact with the springs 65 and the circuit to be closed. When the circuit is 105 closed, the magnet Y, acting on the armature 27, will instantly raise the arm 26 on the rod 25, thereby disengaging the bar M and levers O and P and permitting the spring 37 to ship the belt onto the loose pulley 85 and stop the 110 machine in a manner that will be readily understood by all conversant with such matters without a more explicit description. At the same time the magnet J, acting on the armature L, will disengage the bars G and H and 115 permit the spring b on the shaft E to instantly withdraw the presser f from the needles g, thereby allowing the barbs of said needles to open and prevent the escape of the loops from the shanks of the needles.

120

From the foregoing it will be obvious that the magnets being in circuit and their immediately-connected mechanism operated by electricity, the stoppage of the machine and withdrawal of the presser from the needles will occur simultaneously, thereby preventing the usual injury which occurs to the work by the breakage of threads.

125

For convenience of reference, the cylinder C and needles g are denominated the "knitting-machine proper."

130

Having thus explained my invention, what I claim is—

1. The drop-box R, consisting, essentially

of the case 44, provided with the spring 65, the standard 48, mounted on the insulating-block 47 and provided with the arm 49, and the lever 50, provided with the weight 51, having 5 a thread-groove, 53, and counter-balance 52, combined and arranged to operate substantially as set forth.

2. The sliding shaft E, mounted on the standard D, and provided with the presser f at one 10 end and with adjusting-nuts at the other end, spring b, and collet d, the pivoted bar H, pro-

vided with the catch g, the pivoted bar G, adapted to engage said catch, the sliding rod v, carrying the arm m, and armature L, the magnet J, battery N, and electrical conductors 15 for connecting said magnet and battery, substantially as described.

MATTHEW C. YARWOOD.
